UNITED STATES PATENT OFFICE.

EDWARD C. QUIMBY, OF MINNEAPOLIS, MINNESOTA.

SEPARABLE HINGE FOR AWNING-BLINDS.

SPECIFICATION forming part of Letters Patent No. 634,369, dated October 3, 1899.

Application filed August 14, 1899. Serial No. 727,109. (No model.)

To all whom it may concern:

Be it known that I, EDWARD C. QUIMBY, of the city of Minneapolis, county of Hennepin, State of Minnesota, have invented certain new and useful Improvements in Separable Hinges for Awning-Blinds, of which the following is a specification.

This invention relates to improvements in separable hangers for storm-sash, window-screens, and any sash or frames that it is desired to secure in a readily-removable manner over a window, door, or other opening.

The objects I have in view are to provide a separable hanger that can be stamped or formed out of sheet metal, that will be self-centering, in which the pivotal or turning point of the hanger will be at some distance in front of the plane of the outside surface of the window or sash, and that will have the two parts of the hanger so locked together as to prevent any upward movement of the sash either when the window is closed or open the amount that it is usually opened for airing the room or for other purposes, but which permits a slight upward movement of the sash while it is being closed, so that the sash will pass over any thin coating of ice or other substance that may collect on the upper surface of the edge of the window-sill.

The invention consists generally in a separable hanger consisting of a hook member adapted to be secured to the window-frame or wall and having a projecting hook portion provided with a V-shaped recess in its upper surface at some distance in front of the plane of the wall or window-frame and an eye member adapted to be secured to the window or other sash and having an inclined flange provided with a slot adapted to engage said hook member and to be locked thereon.

The invention further consists in the constructions and combinations hereinafter described, and particularly pointed out in the claims.

In the accompanying drawings, forming part of this specification, Figure 1 is a perspective view of a portion of a window or other sash and frame having my improved separable hanger applied thereto. Fig. 2 is a perspective detail looking at the part of the hanger from the opposite side to that shown in Fig. 1. Fig. 3 is a plan view of the hanger

shown in Figs. 1 and 2. Fig. 4 is a side elevation of the hook member shown in Figs. 1, 2, and 3. Fig. 5 is a perspective view. Fig. 6 is a plan view; and Fig. 7 is a section on line $\alpha\alpha$ of Fig. 6, showing a modified form of one member of the hanger.

In the drawings, 2 represents a portion of a window-sash, screen, or other removable sash or frame that it is desired to secure to a window-frame or other suitable frame or wall in such manner that it may be readily removed therefrom. The separable hanger consists of two members—the hook member 5 and the eye member 7. These parts are preferably formed of sheet metal, and the hook member may be made in the form of a flat sheet or plate, as shown in Figs. 1, 2, 3, and 4. The hook portion of this member is provided with the inclined upper edge 6, the inclined forward edge 8, and the substantially horizontal lower edge 10, having preferably the curved recess 12 located about centrally therein. In the upper edge of the hook member 5 is a V-shaped recess 14, the apex of the V being at some little distance from the front of the outer surface of the window-frame or wall when the hook member is secured in position. This hook member is preferably provided with suitable holes 15, into which suitable screws or nails may be inserted for securing the hook member in position. The hook member instead of being formed as a flat plate, as shown in Figs. 1, 2, 3, and 4, may have its hook portion at right angles to the other part of the member, as shown in Figs. 5, 6, and 7. In this instance the hook member will be secured upon the outside of the window-casing or wall instead of being secured upon the edge of the casing and between the casing and sash, as is done when the hook member is formed as a flat plate, as illustrated in Figs. 1 and 2. The operation of the hook member is the same in both instances.

The eye member 7 of the hanger is provided with an inclined flange 9, having therein a slot 11, which is adapted to receive the hook portion of the hook member of the hanger. The flange 9 is inclined toward the window-sash from the top to the bottom, so that the upper end of the slot 11 stands farther away from the window or other sash than does the lower end. The upper end of the slot 11 rests

in the V-shaped recess 14 in the upper edge 6 of the hook member 5. The slot 11 is of sufficient length to permit its lower edge to just swing under the lower edge 10 of the hook portion of the member 5 when the upper edge of the slot is resting in the V-shaped recess 14. I prefer to provide the curved recess 12 in the lower edge 10 of the hook portion, which allows the sash when being closed 10 to rise slightly, thereby permitting the lower end of the sash to pass over any thin film of ice that may have formed upon the edge of the window-sill. After the lower wall of the slot 11 has passed the recess 12 it will be again 15 brought onto the part of the edge 10 inside of said recess and will thereby be forced down again to its lowermost position and will be locked in this position, as shown in Figs. 1, 2, and 5 of the drawings. As the upper end 20 of the slot 11 and the apex of the recess 14 are both at a point some little distance in front of the surface of the window-frame or wall, the sash may be turned on this support without causing the sash and the eye member of the fastener to move outward, as 25 is necessary with such separable sash-hangers as I am familiar with. In ordinary use the lower end of the sash will be swung outward and fastened by a hook or other suitable fastener; but the lower end of the sash will not 30 ordinarily be moved far enough to bring the lower end of the slot 11 out from under the lower edge 10 of the hook member of the fastener. The V-shaped recess 14 forms a self- 35 centering means for the two parts of the fastener. The recess 12 may, if preferred, be omitted, although I prefer to provide this recess, as it will oftentimes be the means of providing an easy closing of the sash.

40 It will be seen that the fastener is very simple and easy of application and operation. As it may be stamped out of sheet metal, it is cheap in construction. The self-centering feature is of especial advantage. It is also

of especial advantage that the turning-point 45 between the two parts of the hanger be located at a point some little distance in front of the wall of the window-frame when the device is in use, thereby permitting the lower end of the sash to swing outward without causing 50 the eye member to slide forward on the hook member, as is necessary in those forms of separable hanger in which the turning-point between the two parts of the hanger is close against the face of the window-frame. 55

I do not limit myself to the details of the construction herein shown and described, as the same may be varied in many particulars without departing from my invention.

Having thus described my invention, I 60 claim as new and desire to secure by Letters Patent—

1. A separable hinge, comprising a hook member, and an eye member having an inclined flange, with a slot formed in said flange, 65 whereby the turning-point between the two members of the hanger is forward of the surfaces to which the hanger is attached, for the purpose set forth.

2. The combination, in a separable hinge, 70 with the hook member 5 having the vertical hook portion, with a V-shaped recess in its upper edge, of the eye member having an inclined flange, and a vertical slot in said flange, for the purpose set forth.

3. The combination, in a separable hinge, 75 with the hook member 5 having a vertical hook portion, with a recess 12 in its lower edge, of the eye member having a flange inclined from the top toward the bottom, and a slot 11 in 80 said flange, for the purpose set forth.

In testimony whereof I have hereunto set my hand, this 10th day of August, 1899, at Minneapolis, Minnesota.

EDWARD C. QUIMBY.

In presence of—

A. C. PAUL,
M. E. GOOLEY.
